UNITED STATES PATENT OFFICE.

ROBERT H. BEAUMONT, OF RADNOR, PENNSYLVANIA, ASSIGNOR TO R. H. BEAUMONT COMPANY, OF PHILADELPHIA, PENNSYLVANIA, A CORPORATION OF PENNSYLVANIA.

SKIP HOIST.

Application filed January 15, 1923. Serial No. 612,673.

To all whom it may concern:

Be it known that I, ROBERT H. BEAUMONT, a citizen of the United States, residing in Radnor, Delaware County, Pennsylvania, 5 have invented certain Improvements in Skip Hoists, of which the following is a specification.

My invention relates to certain improvements in skip hoists of the type in which a 10 bucket travels on inclined rails to the top of a storage bin and automatically discharges its load into the bin—returning, after it has discharged its load, to be re-filled.

15 One object of my invention is to provide means for preventing the bucket from being inverted and returning in the inverted position.

A further object of the invention is to provide 20 a spring buffer at the top to cushion the blow of the bucket when it is moved to the discharge position.

In the accompanying drawings:

Fig. 1 is a side view of the upper portion 25 of a skip hoist illustrating my invention;

Fig. 2 is a face view of the mechanism shown in Fig. 1;

Fig. 3 is a detached perspective view illustrating the bucket;

30 Fig. 4 is a side view of the upper portion of the hopper, showing the buffer in the raised position;

Fig. 5 is a sectional view of the buffer; and

35 Fig. 6 is an end view of the buffer.

Referring to the drawings, 1 is the frame of the skip hoist supporting a hopper 2 to receive coal, or other material. 3 is an extension of the hopper in which is an opening 4 through which the material is discharged from the bucket 5. 6 is a cover for the opening 4 attached to a lever 7 pivoted at 8. The lever is raised by the bail 9 of the bucket when the bucket is elevated to a point to 40 discharge its load into the opening 4. The bail 9 is pivoted to the bucket 10 and is connected to a rope 11, which is passed around a sheave 12 at the upper end of the structure 13 formed by the rails 14 for the bucket and

50 the braces 15. The rails 14 are inclined, as shown, and terminate at the upper end of the frame 1. Rails 17 form a track less in width than the track formed by the rails 14. These rails 17 extend to the bottom of the structure.

Spaced from the rails 17 are guard rails 18, which prevent the wheels 19 and 20 of the bucket from being displaced as the bucket is raised and lowered on the rails 17. The wheels 19 are flanged, as shown in Fig. 60 2, and are mounted on an axle 21 secured to the bucket. The wheels 19 travel only on the rails 17 and their extensions 17^a, while the wheels 20, which are mounted on axles 65 22, have wider bearing surfaces than the wheels 19 and are flanged at each side and travel on the rails 17 to the upper portion of the frame 1 and then on the rails 14, as shown clearly in Fig. 2. As the bail 9 is pivoted at 10 to the bottom of the bucket, the 70 movement of the wheels on their respective rails causes the bucket to be inverted, as shown in Fig. 1, to discharge its load into the opening 4 in the hopper 2.

In order to prevent the bucket from being 75 fully inverted, arms 23 are provided. These arms are bent at their outer ends 24 to engage the bail, as shown in Figs. 1 and 3, limiting the movement of the bucket. When the bucket mechanism is reversed to allow 80 the bucket to move down the rails into position to receive a load, the bottom of the bucket moves first in the direction of the arrow, Fig. 1, the wheels 19 forming a pivot, the bucket moving down the rails in the 85 correct position.

In order to prevent shocks, due to the sudden inverting of the bucket when the skip hoist is operated at a high speed, a buffer 25 is provided. This buffer consists 90 of two sections pivoted at 26 and supported by springs 27 carried by brackets 28. The upper surface 29 of these sections form continuations of the rails 17^a and are so located that when the bucket 5 is inverted and 95 the upper end thereof falls, the wheels 19 strike the buffer 25, which causes the springs to yield, thus reducing the shock. The buffer, in its normal position, extends above the upper surface of the rails 17^a, as shown 100 in Fig. 4, and, when depressed by the weight of the bucket, is on a line with the rail, as illustrated in Fig. 1.

I claim:

The combination in a skip hoist, of a 105 frame; a hopper supported by the frame and having an opening at its upper end; a door closing the opening; a pivoted arm carrying the door; inclined rails extending over the opening in the hopper and other rails ex- 110

tending to the opening and at an angle to the first mentioned rails; a bucket having wheels adapted to travel on the rails, the rear wheels, when the bucket is above the hopper, traveling on the first mentioned rails and the front wheels traveling on the other rails; a bail pivoted to the bottom of the bucket; means, on the bucket, arranged

to engage the bail when the bucket is partially inverted; and buffers arranged in the path of the front wheels of the bucket, so that, when the bucket is inverted to discharge its load, the shock will be taken by the buffers.

ROBERT H. BEAUMONT.
